CLAIM

The ornamental design for push out grille for a work machine, as shown and described.

DESCRIPTION

FIG. 1 is a top, front perspective view of a push out grill for a work machine embodying our new design in a work machine environment and a hood environment.

FIG. 2 is a top, front perspective view of a push out grill for a work machine in a hood environment;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line representations in the figures show unclaimed environment or boundaries, and thus form no part of the claimed design.
